HANS SCHWEITER, OF HOREN, SWITZERLAND.

MEASURING DEVICE FOR TEXTILE MACHINERY INCORPORATING A SWIFT.

Application filed February 13, 1924, Serial No. 692,580, and in Switzerland March 18, 1923.

This invention relates to measuring devices for that kind of textile machinery incorporating a swift in which after a predetermined number of revolutions of the swift 5 or after a predetermined travel of a measuring screw the machinery is automatically stopped and in which the swift is mounted on an arm.

The main object of my invention is to enable disengagement of the drive of the measuring screw to take place automatically and allow automatic return of the measuring screw to the initial position and to then cause the said drive to again become automatically engaged at the proper time.

I attain this object by the mechanism illustrated in the accompanying drawings, wherein—

Figure 1 is a front elevation, partly in section of a measuring device.

Figure 2 a view in vertical section on line 2—2 of Figure 1 regarded in the direction of the arrow 2.

Figure 3 is a view in vertical section on line 3—3 of Figure 1 regarded in the direction of the arrow 3.

Figure 4 is a view in vertical section similar to Figure 3 but with operative parts of the mechanism shown moved into another position.

Figures 5 and 6 are detached sections in side view illustrating details.

Referring to the drawings, the swift 1, Figure 2, is mounted on an arm 2 which is oscillatable in a forward direction on a pin 4 fixed in the frame 3 of the machine. A pinion wheel 5, is seated on the swift boss and meshes with a pinion wheel 5' seated on a shaft 6 which is mounted in the frame 3. A pinion wheel 7 and a belt pulley 8 are also seated on the shaft 6, and the belt pulley 8 is connected to a driven belt pulley (not shown) by means of a belt 10 which passes over a tension pulley 9, Figures 3 and 4. The tension pulley 9 is adjustably carried by a two-armed hand operated tension lever 11 which is loosely mounted on the shaft 6. In order to enable the tension lever 11 to be maintained in its tensioning position, Figure 4, the following locking device is provided. A three-armed locking lever 13, 14, 15 is rotatably mounted on a stud 12 mounted in the frame 3. The arm 13 serves as a hand grip, the arm 14 has a shoulder 16 adapted to engage a locking roller 17 mounted on the tension lever 11, and the arm 15

carries a stop screw 18 and the end of a spring 19 the other end of which is fixed to the frame, the spring acting to impart a turning movement to the locking lever 13, 14, 15 in a right hand direction and hold it in the locking position, Figure 4.

In this position the stop screw 18 bears against an angular lever 21 mounted loose on a shaft 20.

The locking lever 13, 14, 15 is provided with a brake cheek 22 which is intended, under the pressure of the roller 17 of the released tension lever 11 on the arm 14 of the locking lever 13, 14, 15 to press itself against the inner surface 71 of the belt pulley 8 and brake the said belt pulley. A rod 23 with collar 24 and spring 25 is pivotally connected to one arm of the angular lever 21.

This spring presses on the one hand against the collar 24 which is adjustable for the purpose of regulating the spring tension and on the other hand against a stud 26 having a hole in which the rod 23 slides.

The stud 26 is provided on a locking pawl 27 and the spring 25 therefore acts on the pawl 27 through the stud 26. The stud 26 is mounted to swivel on the pawl 27 to allow freedom of movement between the rod 23 and the pawl 27. This pawl is intended, as

will be hereinafter more fully explained, to hold the tension lever 11 in its position of release (Figure 3) up to a predetermined moment. The tension lever 11 is provided with a lateral catch pin 28. A pin 29 limits the turning movement of the angular lever 21 in the left hand direction. The pinion 5', Figure 1, is provided with a carrier pin 30 which at each rotation imparts a partial rotation to a wheel 31 secured by means of a screw 72 to a shaft 31^a journaled in the frame 3. The shaft 31^a furthermore carries a disc 32 having a driving pin 33, Figures 1 and 2, which at each rotation of the disc 32 imparts a partial rotation to a second 100 toothed wheel 34. The toothed wheel 34 is provided with an elongated pinion 35 which meshes with a toothed wheel 36. The wheel 36 is fixed on the measuring screw 37 and the said measuring screw is screwed into a swing frame 38 mounted loose on the shaft 20. The left hand end of the measuring screw 37 carries a member 39 serving as a cord drum and provided with two flanges 40 and 41 provided with pins 42 and 43 respectively. The pin 42 is intended to press against the angular lever 21 after a prede-

terminated number of revolutions of the measuring screw 37 and to turn it in a right hand direction. The pin 43 is intended to limit the rotary return movement of the measuring spindle 37 by impinging on a pin 46 which is slidably mounted on the swing frame 38, the return movement of the measuring screw 37 being effected by a cord 44 wound on the member 39 and having a 10 weight 45 suspended on it.

The pin 46 is connected to a pointer 50 by means of a cross pin 47, the pointer 50 being pivotally mounted at 48 on the swing frame 38 and having a knob 49.

15 A scale 51 provided on the swing frame 38 enables the position of the pointer and therefore the measured lengths to be read off, and the lengths indicated can be varied between, for example, 225 metres and 3600 20 metres by the aid of suitable changes in the transmission ratios between the shaft 6 and the shaft 31^a. Measuring always takes place from the set number of metres to the zero point.

25 A ring 52, Figures 1 and 6, is seated on the right hand end of the shaft 20 and has two tappets 53 and 54 between which engages the bent end of a rod 55 connected to the swift carrying arm 2. As will be observed from the drawing, the swing frame 38 has a rectangular gap in it where it is engaged by the shaft 20, and the shaft 20 crosses the gap and supports the frame 38 at both sides of the gap. A cam 56 is situated in the said gap and is fixed to that part of the shaft 20 which crosses the gap. The shaft 20 can therefore oscillate the cam 56 in the said gap without oscillating the frame 38. The cam 56 has two abutment surfaces 30 57 and 58. The surface 57 is intended to impinge on a surface 59 of the swing frame 38 and to impart thereto a rearward swing, whilst the surface 58 is intended to impinge against a surface 60 of the swing frame 38 and swing the frame in a forward direction. The parts 56, 57, 58, 59 and 60 35 therefore form a so-called slipping coupling between the shaft 20 and the swing frame 38. A spring 61, connected on the one hand to the frame 3 and on the other hand to the swing frame 38 acts to turn the swing frame 38 forwardly, that is to say towards the right hand in the view illustrated in Figure 2, and to yieldingly bring the wheel 36 again into engagement with the elongated pinion 35 if it has been brought 40 out of engagement therewith, the wheel 36 then being positively held in engagement by the pressure of the surface 58 against the swing frame 38.

On the left hand end of the shaft 20 is provided a so-called spring rocker, Figures 1 and 5. This spring rocker consists of a sector 62 possessing two stop screws 63 and 64 which co-operate with stop surfaces 65 45

and 66 of the frame to limit the angular movement of the swing frame 38. A spring 67 has one end connected to the frame 3 at a point vertically beneath the axis of the shaft 20 and has its other end attached to 70 the sector 62 at the middle thereof. The drive of the yarn guide is effected from the wheel 7 by means of a wheel 68 and a chain drive 69, 70.

The mode of operation on the hereinbefore described measuring device is as follows:—

During running of the machine the starting and stopping device is in the position illustrated in Figure 4. The belt 10 is held 80 tight by the tension lever 11 and the said lever is locked by the locking lever 13, 14, 15.

The measuring screw 37 is rotated from the belt pulley 8 by means of the gearing 30 to 34 and the gearing 35, 36. The swift 85 1 has motion imparted to it through the gearing 5, 5' and the yarn guide (not shown) is operated from the gearing 7, 68 and the chain gearing 69, 70.

When the measuring screw 37, which is 90 moving towards the left, Figure 1, reaches the zero point, the pin 42 of the measuring screw impinges against the angular lever 21 and turns it towards the right hand, Figure 3. The lever 21 acts on the stop screw 18 on the lever arm 15 and the locking lever 13, 14, 15 is thereby turned against the pull of the spring 19. The roller 17 of the tension lever 11 is thus relieved from the retaining action of the shoulder 16. The tension lever 11 is thereby freed and swings out of the position shown in Figure 4 into the position shown in Figure 3 and the driving belt 10 is thereby loosened and the drive ceases. At the same time the rod 23 is 105 lifted, the spring 25 is compressed, and the pawl 27 snaps behind the catch pin 28 of the tension lever 11 thus preventing the said lever from being operated accidentally with the result of tightening the belt, until the spring 25 is released. On the oscillation of the tension lever 11 out of the position shown in Fig. 4 into that shown in Figure 3, the roller 17 presses on the arm 14 of the locking lever 13, 14, 15 with the result that the brake shoe 22 is pressed against the belt pulley 8 and brakes the same.

Furthermore the swift carrying arm 2 is swung forwards, that is to say towards the right hand in Figure 2, in order to take off 120 the hank or skein.

On this movement taking place, the shaft 20 is turned by the rod 55 and the tappet 54 in the direction of the arrow P, Figure 6. As soon as the spring 67 has passed 125 its dead point during this turning movement, the said spring completes the turning movement of the shaft 20 in the hereinbefore named direction. The cam surface 57 impinges against the frame surface 59 and 130

oscillates the frame 38 in the return direction, that is to say towards the left in Figure 2, whereby the wheel 36 becomes disengaged from the elongated pinion 35 and the measuring screw 37 is freed. The weight 45 and cord 44 now rotate the screw 37 backwards until the pin 43 impinges against the pin 46 which has been adjusted to give the desired measure of length.

10 Owing to the rotation of the shaft 20 effected by the spring 67 in the direction of the arrow P, Figure 6, the rod 23 has become lifted to a further extent and the spring 25 has become more compressed.

15 After the hank or skein has been removed, the swift carrying arm 2 is swung back into its initial position and the rod 55 thereby acts on the tappet 53 and rotates the shaft 20 in the direction of the arrow

20 Q, Figure 2. Immediately the cam surface 57 leaves the swing frame 38 free, the spring 61 again swings the frame in a forward direction that is to say towards the right hand in Figure 2, and the wheel 36 comes into

25 yielding engagement with the elongated pinion 35. As soon as the spring 67 has passed the dead point during the return movement of the shaft 20 the said spring returns the shaft 20 fully into the initial position and

30 the cam surface 58 then renders engagement of the wheels 36 and 35 positive by impinging against the frame surface 60. On rotation of the shaft 20 in the direction of the arrow Q, the angular lever 21 is brought

35 into its initial position, the rod 23 is lowered and the spring 25 is released from compression. The pawl 27 is therefore free to fall by its own weight and releases the tension lever 11. This lever can therefore

40 now be moved into its tightening position, Figure 4, and when so moved the roller 17 again comes under the retaining action of the shoulder 16 and the tension lever becomes locked. On the small rotary move-

45 ment in a right hand direction of the locking lever 13, 14, 15 when the roller 17 falls against the shoulder 16, the brake shoe 22 is caused to be lifted away from the belt pulley 8 by the said movement. The machine then again commences a fresh wind-
50 ing operation.

At the left hand end of the shaft 6, Figure 1, a wheel corresponding to the wheel 5', but without a driving pin 30 can be provided for operating a second swift. This second swift would be carried by a second swift carrying arm 2 which would be oscillatably mounted on an extended pin 4. In this arrangement one measuring device 55 would therefore serve two swifts. The two arms 2 provided in this arrangement would be connected together in order to ensure their simultaneous movement.

What I claim is:-

65 1. A measuring device for a textile ma-

chine incorporating a swift, comprising a measuring screw mounted on the machine; an oscillatable swift carrying arm mounted on the machine; a measuring screw drive for displacing the measuring screw from an initial position; disengaging means for throwing the measuring screw drive out of action; actuating means on the said arm for actuating the disengaging means; means acting on the measuring screw to return it into its initial position on operation of the drive disengaging means; and engaging means on the said arm for bringing the measuring screw drive into action.

2. A measuring device for a textile machine incorporating a swift, comprising a measuring screw mounted on the machine; an oscillatable arm mounted on the machine and carrying the swift; a measuring screw drive on the machine for rotating the screw out of an initial position; means operated from the said arm for disengaging the measuring screw drive; means acting on the measuring screw to automatically return it to the said initial position on disengagement of the said drive; and adjustable stop means provided on the machine for regulating the said initial position of the measuring screw and thereby the measure of length.

3. A measuring device for a textile machine incorporating a swift, comprising a measuring screw mounted on the machine, an oscillatable arm mounted on the machine and carrying the swift; a disengageable measuring screw drive for rotating the screw out of an initial position; means acting on the measuring screw to automatically return it to the said initial position on disengagement of the said drive; stop means provided on the machine for regulating the return movement of the measuring screw and thereby the measure of length; pointer means connected to the stop means for adjusting the stop means; a drive disengaging device on the machine for stopping the swift; and two stop members on the machine in operative connection with the measuring screw, one of which cooperates with the said stop means to bring into action the measuring screw returning means and the other of said stop members brings into action the said drive disengaging device.

4. A measuring device for a textile machine incorporating a swift, comprising a frame provided on the machine; a measuring screw mounted on the frame; an oscillatable swift carrying arm mounted on the machine; a measuring screw drive on the machine to rotate the screw out of an initial position; drive disengaging means operated from the said arm, means acting on the measuring screw for returning it to the said initial position on disengagement of the said drive; stop means provided on the machine for regulating said initial position of the

- measuring screw and thereby the measure of length; a belt drive for the swift; a belt tension controlling lever on the machine for rendering the belt drive operative and inoperative; locking means for locking the belt tightening lever in its tightening position; an angular lever for throwing the locking means out of action; and means on the measuring screw for actuating the angular lever.
10. 5. A measuring device for a textile machine incorporating a swift, comprising a measuring screw mounted on the machine; an oscillatable swift carrying arm mounted on the machine; a measuring screw drive on the machine for moving the measuring screw out of an initial position; means set in motion by movement of the said arm for automatically returning the measuring screw to the said initial position; stop means provided on the machine for adjusting the said initial position and thereby the measure of length; a belt drive for the swift; a belt tension controlling lever on the machine for rendering the belt drive operative; an angular lever on the machine acting on the belt tension controlling lever; a pin on the measuring screw acting on the angular lever; a catch pin provided on the belt tension controlling lever; a locking pawl oscillatably mounted on the machine to engage the catch pin; and a rod resiliently connected to the pawl and controlled by the angular lever for producing engagement of the pawl with the catch pin and thereby locking the belt tensioning lever in inoperative position.
6. A measuring device for a textile machine incorporating a swift, comprising a governing shaft which is oscillatably mounted on the machine; an arm oscillatably mounted on the governing shaft; a measuring screw rotatably mounted on the said arm to oscillate therewith; a driven toothed wheel on the machine; a toothed wheel fixed to the measuring screw and adapted to mesh with the driven toothed wheel and thereby rotate the measuring screw; a member provided on the governing shaft to oscillate therewith; abutment surfaces on the said member; and complementary abutment surfaces on the said arm lying in the path of the abutment surfaces on the said member and acted on by the last named surfaces for transmitting a part of the oscillatory movement of the governing shaft to the said arm and thereby alternately bringing the toothed wheel on the measuring screw into and out of engagement with the driven toothed wheel on the machine.
7. A measuring device for a textile machine incorporating a swift, comprising a governing shaft oscillatably mounted on the machine; an arm oscillatably mounted on the governing shaft; a measuring screw rotatably mounted on the said arm to oscillate therewith; a driven toothed wheel on the machine; a toothed wheel fixed to the measuring screw and adapted to mesh with the driven toothed wheel and thereby rotate the measuring screw; a member provided on the governing shaft to oscillate therewith; abutment surfaces on the said member; complementary abutment surfaces on the said arm acted on by the said abutment surfaces on oscillation of the governing shaft in one direction for oscillating the frame and thereby moving the toothed wheel on the measuring screw out of engagement with the driven toothed wheel; a collar provided on the governing shaft for oscillating the said shaft; tappet arms provided on the collar for oscillating the collar; a swift carrying arm oscillatably mounted on the machine; a rod connected to the swift carrying arm and acting on the said tappets for transmitting oscillatory movement in one direction from the swift carrying arm to the tappets; and a spring shift means provided on the governing shaft for acting on the said shaft in its direction of oscillation and thereby continuing to completion the movement of the governing shaft initiated by the swift carrying arm through the medium of the rod and tappets.

Signed at Zurich, in the Canton of Zurich, Switzerland, this 24 day of January, 1924.
